[57] CLAIM

The ornamental design for a shoulder pad for violin or
the like, as shown and described.

DESCRIPTION

FIG. 1 is a perspective view of a shoulder pad for a
violin or the like showing my new design;

FIG. 2 is a side elevational view taken from FIG. 1 that
has been turned upside down;

FIG. 3 is a bottom plan view of FIG. 1;

FIG. 4 is a top plan view of FIG. 1.

FIG. 1

FIG. 2

FIG. 3

FIG. 4
